UNITED STATES PATENT OFFICE.

LOUIS WELKER, JR., OF WILLIAMSPORT, PENNSYLVANIA, ASSIGNOR TO THE NEW HOME SEWING MACHINE COMPANY, OF ORANGE, MASSACHUSETTS, A CORPORATION OF MASSACHUSETTS.

SEWING-MACHINE DRIVING MECHANISM.

Application filed April 4, 1921. Serial No. 458,182.

To all whom it may concern:

Be it known that I, LOUIS WELKER, Jr., a citizen of the United States, and resident of Williamsport, in the county of Lycoming and State of Pennsylvania, have invented certain new and useful Improvements in Sewing-Machine Driving Mechanism, of which the following is a specification.

This invention relates primarily to sewing machine driving mechanism for use in connection with a sewing machine mounted on a so-called "drop-head" stand or cabinet, where the sewing machine head is adapted to be shifted from an operative or sewing position above the table top of the stand when in use, to an inoperative position below the same when not in use.

The usual form of driving mechanism for foot-operated machines, as well known, comprises a large driving wheel mounted on the stand below the table top and having belt connection with the machine pulley, and an operating foot-treadle having a pitman connection with a crank fixed to the driving wheel for imparting rotary movement to the latter. With such combination of parts, the driving wheel and the machine pulley are of course in vertical alignment with each other when the machine is in use, and in order to permit of the lowering of the machine below the table without contact with the driving wheel, some provision has been made to shift the machine to one side of the vertical plane of the driving wheel before or during the lowering of the same. The means providing for such lateral shifting of the machine, however, has been more or less complicated and expensive, and it has therefore been an object of my present invention to provide an improved means for permitting of the raising or lowering of the machine without interference with the driving wheel that will be both simple and inexpensive. This object, and others to be herein-after referred to, are attained by the novel features of construction and combination of parts embodying my invention as illustrated in the accompanying drawings, in which—

Fig. 1 is a front elevation of a sewing machine stand or cabinet equipped with my invention, the same being closed and the machine head and operating parts therefor being located in their inoperative positions.

Fig. 2 is a top plan of the same with the

stand opened and the machine in raised position for use.

Fig. 3 is a vertical transverse section taken on the line 3—3 of Fig. 2, looking in the direction indicated by the arrows.

Fig. 4 is a vertical longitudinal section taken on the line 4—4 of Fig. 3, looking in the direction indicated by the arrows.

Fig. 5 is a fragmentary sectional detail, the section being taken on the line 5—5 of Fig. 1, showing a hinged door section forming part of the front panel of the stand.

Fig. 6 is an enlarged detail, with the parts partly broken away and in section, showing the adjustable connection of the driving wheel with its supporting crank shaft.

To explain in detail, the stand or cabinet here shown upon which the machine and its operating parts are mounted comprises four supporting legs, each indicated at 2, having a table top 3 formed with an opening 4 for the passage of the machine, and an extension leaf 5 hinged at one end to said table 3, as at 6, and adapted to be folded over the latter to close the opening therein when the machine is not in use, as shown in Fig. 1.

The machine 7 is hinged to the table 3 at the rear edge of the opening 4, as indicated at 8—8, and is supported at its front edge when in raised position on brackets 9, 9, secured to the under side of a hinged table section 10, which latter is adapted to be raised, as shown by dotted lines in Fig. 3, to permit of the lowering of the machine below the table.

The machine 7 is provided with the usual grooved pulley 11 which is adapted to be driven through a belt 12 from a driving wheel 14 supported below the table 3. This wheel 14, in the present case, is mounted on a crank shaft 15 which is journaled at its opposite ends in bearings 16 and 17 suitably attached to the stand. In accordance with my invention, the shaft 15 is made of sufficient length to permit of the wheel 14 being adjusted lengthwise thereof from an operative driving position in alignment with the machine pulley, as shown by full lines in Fig. 4, to an inoperative position at one side of the vertical path of movement of the machine when being lowered from operative to inoperative position, as indicated by dotted lines in Fig. 4. This lateral adjustment of the driving wheel with respect to the path

of movement of the machine permits of the use of a simple hinge connection between the machine and table, thus obviating the need of the somewhat involved and more expensive means usually employed for effecting the lateral shifting of the machine with respect to the driving wheel.

The driving wheel has a splined connection with the crank shaft, as clearly indicated at 18 in Fig. 6, for permitting of its sliding adjustment, and is adapted to be secured in its operative position thereon by a suitable fastening device, such as the spring-pressed pin 19 carried by the hub of the wheel for engagement with the shaft within a hole 20 therein. The crank shaft and connected driving wheel are adapted to be operated in usual manner from a pivoted foot-treadle 21 on the base 20 of the stand through a connecting pitman rod 22.

In some instances it may be desired to operate the machine by power rather than by the manual means described. For this purpose I provide an electric motor of usual construction, as indicated generally by dotted lines at 28, which is pivotally mounted at 29 on a bracket 30 for movement to and from an operative position with its shaft pulley 31 in driving engagement with the machine pulley, as shown in Fig. 3. Interposed in the electric circuit of this motor is a rheostat, indicated diagrammatically at 32, the controller 33 of which is adapted to be operated from the treadle 21 through a chain or similar flexible connection 34 operating over a guide wheel 35, the movement of the controller as effected by the treadle for regulating the speed of the motor being against the tension of a spring 36, which latter connects at one end with the controller and at its opposite end with a staple 37 or other fixed part of the stand, as shown in Fig. 4.

When the machine is to be operated by the motor, the driving wheel 14 and its crank will of course be disconnected from the treadle so as to allow of independent operation of the treadle in its control of the motor through the rheostat 32. This is provided for by making the pitman 22 in two sections and detachably connecting them at their adjacent ends by a sleeve 38 fixed on one section and detachably connected to the end of the other section by a suitable fastening device, such as the screw 39. By loosening this screw 39, a lowering of the treadle or a raising of the crank will act to withdraw one pitman section in an endwise direction from connection with the other, and so permit of the treadle being employed to regulate the electric current through the rheostat without causing operation of the driving wheel. On the other hand, when the driving wheel is to be used

to operate the machine, the chain 34, which is detachably connected to the treadle by a hook 40, will be disconnected from the treadle and the pitman sections be again placed in connection by the fastening device 39.

For enclosing the machine and its driving mechanism when not in use, the stand is enclosed on its four sides at the upper part thereof by panels 45, a section of the front panel being hinged, as at 46, to permit of ready access to the enclosed part of the stand and also to a tool or other receptacle, such as 47, attached to the inner side of the panel. A catch device 48 serves to normally hold this hinged panel in closed position, as best shown in Fig. 5. A partition 49, extending from the front to the rear panel, partly at an incline as shown in Fig. 3, serves to enclose the machine from the under side thereof. A chamber or receptacle 50, formed between this partition 49 and the rear panel 45, contains the rheostat 32.

In order that the treadle, as well as the machine, may be covered from view when the machine is not in use, I also provide a shelf 51 for location directly over the treadle, as shown in Fig. 1. This shelf is hinged to the rear legs of the stand, as at 53, to permit of its being swung backward to expose the treadle when the machine is to be used, and is here shown (see Fig. 3) as being formed in two sections hinged together to permit of its being partially collapsed for backward movement in the somewhat limited space below the panelled or enclosed part of the stand. A strip or cleat 54 on the under side of the shelf at the front edge thereof has laterally projecting ends 55 which engage with the rear legs to limit the backward movement of the shelf, as shown in Fig. 4.

When the machine is in lowered position and the upper extension leaf 5 and lower shelf 51 are both placed in closed positions, the machine and its operating parts are fully covered from view, as will be clear by reference to Fig. 1, whereby the stand or cabinet becomes an attractive article of furniture without any indication of its real purpose as a support for a sewing machine and its operating mechanism.

What I claim is:

1. In combination, a sewing machine stand having a table-top, a sewing machine having a driving pulley, means supporting said machine for movement from an operative position above the table to an inoperative position below the same, a driving wheel and support therefor below the table, the driving wheel being laterally adjustable on its support from a driving position in alignment with the machine pulley when the machine is raised to an inoperative position at one endwise direction from connection with the other, and so permit of the treadle being employed to regulate the electric current through the rheostat without causing operation of the driving wheel.

side of the path of movement of the machine pulley when the machine is being lowered, a driving connection from the driving wheel to the machine pulley, and operating means for the driving wheel.

2. In combination, a sewing machine stand having a table top, a sewing machine having a driving pulley and being hinged to said table for swinging movement in a vertical plane from an operative position above the table to an inoperative position below the same, a driving wheel and support thereof below the table, the driving wheel being laterally adjustable on its support from a driving position in alignment with the machine pulley when the machine is raised to an inoperative position at one side of the path of movement of the machine pulley when the machine is being lowered, a driving connection from the driving wheel to the machine pulley, and operating means for the driving wheel.
- 10 15 20

3. In combination, a sewing machine stand having a table top formed with an opening, a sewing machine having a driving pulley and being hinged to said table at one edge of the opening therein for swinging movement through the opening from an operative position above the table to an inoperative position below the same, a crank shaft mounted in bearings on the stand below the table, a driving wheel mounted on said crank shaft to be driven thereby and being laterally adjustable thereon from a driving position in alignment with the machine pulley when the machine is raised to an inoperative position at one side of the path of movement of the machine pulley when the machine is being lowered, means for adjustably securing the driving wheel in fixed connection with the crank shaft, a belt connection from the driving wheel to the machine pulley, a pivoted foot treadle, and a driving connection from said foot treadle to the crank shaft.
- 25 30 35 40 45

4. In combination, a sewing machine stand, a sewing machine and a driving crank therefor both supported by said stand, a foot treadle operatively connected with said driving crank, and a shelf for covering the treadle when the machine is not in use, said shelf being hinged to the stand at the rear thereof and formed in sections hinged together whereby it may be partially collapsed for backward movement in a limited space to a position to expose the treadle when the machine is to be used.
- 50 55

5. In combination, a sewing machine stand, a sewing machine and a driving crank therefor both supported by said stand, a foot treadle, a pitman connection from said treadle to the driving crank, said pitman connection being divided at a point between its ends and the sections thereof adjustably
- 60

connected together whereby the lower or treadle section may be disconnected from the crank section and dropped to a lowered position adjacent the treadle, and a shelf connected with the stand in position for covering the treadle and connected pitman section when the machine is not in use and being movable from such position to expose the treadle when the machine is to be used.

6. In combination, a sewing machine stand, a sewing machine mounted thereon and having a driving pulley, a driving wheel, a belt detachably connecting said wheel with the driving pulley, an electric motor having a pulley for driving engagement with the machine pulley and being movable to and from a position for effecting such engagement, a rheostat in the motor circuit having a controller arm, and a foot treadle having separate operative connections to the driving wheel and the rheostat controller, said connections each being detachable from the treadle to permit of the use of one independent of the other.

7. In combination, a sewing machine stand having a table top, a sewing machine having a driving pulley, means supporting said machine for movement from an operative position above the table to an inoperative position below the same, a driving wheel and support therefor below the table, the driving wheel being laterally adjustable on its support from a driving position in alignment with the machine pulley when the machine is raised to an inoperative position at one side of the path of movement of the machine pulley when the machine is being lowered, an electric motor adapted to be brought into driving engagement with the machine pulley, and a foot treadle having separate operative connections with the driving wheel and the motor, said connections each being detachable from the treadle to permit of the use of one independent of the other.

8. In a sewing machine of the class described the combination with a sewing machine stand, a sewing machine pulley mounted on said stand, a drive wheel adjustably supported below said sewing machine and adapted to be brought into vertical alignment with said drive pulley, a driving connection between said pulley and wheel, an electric motor adapted to be brought into driving engagement with said drive pulley, a foot treadle separately connected to said driving wheel and said motor, said connections each being detachable from the treadle to permit of the use of one independent of the other.

Signed at Williamsport, in the county of Lycoming and State of Pennsylvania, this 30th day of March, A. D. 1921.

LOUIS WELKER, JR.
